C. BOOZE.

WALL PAPER.

Patented Oct. 21, 1890.

UNITED STATES PATENT OFFICE.

CHARLES BOOZE, OF BUFFALO, NEW YORK, ASSIGNOR TO M. H. BIRGE & SONS, OF SAME PLACE.

DESIGN FOR WALL-PAPER.

SPECIFICATION forming part of Design No. 20,226, dated October 21, 1890.

Application filed September 27, 1890. Serial No. 366,384. Term of patent 3½ years.

To all whom it may concern:

Be it known that I, CHARLES BOOZE, a citizen of the United States, residing at Buffalo, in the county of Erie and State of New York, 5 have invented and produced a new and original Design for Wall-Paper, of which the following is a specification, reference being had to the accompanying photograph, forming part thereof.

10 The leading feature of my design consists of vines and leaves of the ivy, with small stencil flowers among the leaves upon a background composed of irregular broken lines arranged horizontally and vertically, as represented in the accompanying photograph. 15 The vines are intertwined and run in various directions to cover the surface of the paper. The paper is tinted in any desired color.

What I claim is—

The design for wall paper herein shown and 20 described.

Witness my hand this 13th day of September, 1890.

CHARLES BOOZE.
